UNITED STATES PATENT OFFICE.

PATRICK J. HUBIN, OF CLIFTON, NEW JERSEY.

VALVE.

1,412,746.

Specification of Letters Patent. Patented Apr. 11, 1922.

Application filed October 12, 1920. Serial No. 416,384.

To all whom it may concern:

Be it known that I, PATRICK J. HUBIN, a citizen of the United States, and a resident of Clifton, in the county of Passaic and 5 State of New Jersey, have invented a new and Improved Valve, of which the following is a full, clear, and exact description.

My invention relates to valves, and more particularly to valves having a thermostatic 10 action, my more particular purpose being to provide a valve and mechanism associated therewith for use upon radiators and the like.

My invention comprehends a heat-controlled and self-closing valve carried in a casing, so arranged that the casing and its 15 contents can be removed together as a unit and in practice may be treated much after the manner of a joint of pipe.

20 The object of the invention is to provide a thermostatic or automatic air valve for use on radiators of steam heating systems so as to permit the air in the system and particularly in the radiators to escape or exhaust to 25 facilitate the entrance of steam and hasten the heating action, and to close under the action of heat from the steam so as to prevent the escape thereof, thereby insuring of a more efficient heating action.

30 Reference may be had to the accompanying drawing forming a part of the specification, in which like characters of reference indicate like parts throughout the several figures.

35 Figure 1 is a side elevation showing my improved mechanism as applied to a radiator; and

Figure 2 is a fragmentary view, partly 40 in section, and partly broken away, and showing the details of the valve mechanism.

A boiler appears at 3 and located over the same is a floor 4. A pipe 5 extends from the boiler 3 to a radiator 6, communication through this pipe being controlled by means 45 of a valve 7.

An air pipe is shown at 8 and terminates at 9 in a flue 3^a, so arranged that there is at all times maintained a partial vacuum within the air pipe 8.

50 My improved valve casing appears at 11 and is connected by a coupling 10 with the air pipe 8. The valve casing 11 is provided with a screw cap 12 detachably fitted upon it, and by removing this cap the mechanism 55 within the casing is readily removed.

The casing 11 is provided with a cylind-

rical compartment 14 and with a pair of passages 15, 16 communicating with this compartment. A screw plug 17 is fitted into the compartment 14 and for this purpose 60 is provided with a threaded upper portion 18, the interior of the casing 11 being threaded to match the same. The screw plug 17 is further provided with a slot 19 into which a screw driver is inserted for the 65 purpose of turning the screw plug and thereby adjusting it or effecting its removal.

The screw plug 17 is made of expansible metal, that is, metal having a high coefficient of expansion from heat, and is provided with a reduced smooth or unthreaded lower portion 20 to freely move or expand in the casing. This reduced portion is provided with a recess or guide socket 21 extending axially up into it a little distance 70 at the bottom, as indicated in Figure 2. A valve is shown at 23 and is provided with a stem 24 extending axially thereof or through it, this stem being provided with a protruding portion 25 of reduced diameter 75 at the bottom and disposed in the passage 16, while the stem 24 extending upwardly from the top is disposed in the recess or guide socket 21. The valve 23 normally falls by its weight and closes the passage 80 16 due to the tapered or conical lower portion thereof and said valve is guided in its movements by engagement of the stem 24 and the portion 25 with the recess and passage respectively. 90

The operation of my device is as follows: With the furnace and boiler in action, a partial vacuum is formed within the pipe 8, and this tends to allow an expansion of air within the radiator 6. When the radiator is heated it is, of course, heated with steam, and this steam displaces any air remaining within the radiator. The air passes out through the passage 16 and in so doing lifts the valve 23. By the time the air is 95 all out of the radiator the screw plug 17, by its expansion from the increasing heat, forces downwardly and moves the valve 23 against its seat so as to close the passage 16. When this is accomplished there is no 100 escape of steam from the radiator past this valve. 105

Referring more particularly to Figure 2, it will be noted that the valve 23, and all parts immediately associated therewith, together with the screw plug 17, are contained within the casing 11, and that this 110

casing has such simple form that it may in practice be treated merely as a short piece of piping.

The casing 11 with its contents may thus be considered as an article of manufacture, in which the various parts are all self contained.

In order to adjust the screw plug 17, so as to adjust the sensitiveness of the device to varying degrees of heat, the cap 12 is removed, a screw driver inserted in the slot 19, and the screw plug turned to a greater or less extent until the adjustment is satisfactory.

15 My purpose in connecting the air pipe 8 with the flue 3^a is to enable the air to be removed from the radiator even when the steam pressure in the boiler is very low.

When the steam pressure goes down, the seating of the valve 23 will close the passage 16 and thus prevent the entrance of air. Thus a lowering of the steam pressure does not cause air to enter the radiator. It is only in instances where the air creeps in as, for instance, after the boiler has been cold for several hours, that the valve 23 must be lifted in order to allow the escape of air as above described.

I do not limit myself to the precise mechanism shown, as variations may be made therefrom without departing from my invention, the scope of which is commensurate with my claims.

Having thus described my invention, I claim as new and desire to secure by Letters Patent:—

1. A valve of the class described comprising a casing having an outlet extending through the bottom thereof and an inlet extending axially through the bottom and laterally through the side of the casing, a

plug adjustably mounted in the casing and formed of material having a high coefficient of expansion, the lower portion of the plug being spaced from the inner surface of the casing and the lower end thereof being spaced from the bottom of the casing, said plug having an axial recess in the bottom, a valve disposed to normally close the inlet and having stems engaging the axial portion of the inlet and the recess to guide the valve in its movement, said plug when expanded holding said valve against its seat.

2. A valve of the class described comprising a cylindrical casing provided with an interiorly threaded upper portion and a smooth lower portion, said casing having a downward extension and a passage leading into the same from the bottom of the casing to form an outlet, an attaching stem

projecting at one side of the casing near the bottom thereof and provided with an inlet passage extending to the axis of the casing and upwardly through the bottom thereof an expansible plug having a threaded upper portion engaging the interior threads of the casing and provided with means whereby it may be turned to adjust it in the casing, said plug having a reduced unthreaded lower portion spaced from the interior wall of the casing and an axial recess in its bottom, a valve between the lower end of the plug and the bottom of the casing and having a conical portion cooperating with the inlet passage to normally close the same and having a reduced downwardly extending axial stem engaging said inlet passage and an upwardly extending stem engaging the recess for guiding the valve in its movement, and a cap on the casing over the plug.

PATRICK J. HUBIN.
